UNITED STATES PATENT OFFICE.

FREDERICK E. CHAPMAN, OF MIDDLETOWN, CONNECTICUT.

DESIGN FOR A BUTTER-DISH.

49,011.

Specification for Design.

Patented May 9, 1916.

Application filed February 2, 1916. Serial No. 75,838. Term of patent 14 years.

To all whom it may concern:

Be it known that I, FREDERICK E. CHAPMAN, a citizen of the United States, residing at Middletown, in the county of Middlesex and State of Connecticut, have invented a new, original, and ornamental Design for a Butter-Dish, of which the following is a specification, reference being had to the accompanying drawing, forming a part thereof.

Figure 1 is a front elevation of a butter

dish, illustrating my new design. Fig. 2 is a side elevation of the same. Fig. 3 is a plan view of the same.

I claim:—

The ornamental design for a butter dish, as shown.

FREDERICK E. CHAPMAN.

Witnesses:

BERTRAND E. SPENCER,
OLGA P. BRAINARD.
